SIDE-STRIPPING CARTRIDGE BELT LINK

Burns Darsie, Rockford, Ill., assignor to the United States of America as represented by the Secretary of the Army

Application December 14, 1954, Serial No. 475,320

8 Claims. (Cl. 89—35)

This invention relates to ammunition belts and more particularly to a disintegrating cartridge link belt wherein the connection between adjacent links is effected by means independent of the cartridges associated therewith.

High-speed machine guns and automatic cannon are customarily supplied with cartridges which are belted together by means of a plurality of identical link members of the type wherein a connecting loop on one link fits between a pair of spaced-apart cartridge-gripping loops on the adjacent link to form a hinge in which the cartridge itself acts as a pintle. Experience has indicated that the aforesaid type of cartridge belt link is particularly well adapted for use with those firearms wherein the feeding mechanism thereof is designed to push or pull each cartridge out of engagement with the links associated therewith along an axis substantially in alignment with or parallel to the bore axis of the firearm barrel. However, certain other firearms utilize feeding mechanisms which prepare the cartridges for chambering by camming them laterally out of the links associated therewith and consequently require that the connection between adjacent links consists of means other than the disintegrating coupling provided by the cartridge itself.

One such type of cartridge belt link comprises a unitary member adapted to hold a single cartridge and joined to the adjacent link by an independent connector. While this type of link connection is particularly adapted for cartridge feeding mechanisms which extract or, as is more commonly termed, "strip" the cartridges laterally from the belt, experience has indicated that separate link connectors are unable to withstand the high loads imparted thereto in the operation of high-speed aircraft firearms. These high loads are due to the combination of the axial pull produced by the transverse feeding movements of the ammunition belt toward the firearm and the helical pull produced by the turning and twisting movements between adjacent links during the passage of the ammunition belt out of the storage box and around the various feed and guide rollers or chutes which are normally provided in the confined quarters customarily encountered in aircraft mountings. Attempts to strengthen the cross-sectional area of these independent connectors sufficiently to prevent breakage have invariably reduced the relative flexibility between adjacent links below the minimum amount necessary to follow the convolutions of conventional chuting which often provide as much as a 90° change in direction. Other attempts to strengthen these connectors by suitable heat treatment or selection of special alloys have been equally unsuccessful or at best have resulted in such added expense as to prohibit practical mass production of expendable type links.

Accordingly, it is an object of this invention to provide an improved cartridge belt link of the type in which the cartridges are stripped laterally therefrom.

It is a further object of this invention to provide an improved cartridge belt link which does not require the

2

use of the cartridge itself to effect a disintegrating connection between adjacent links.

Still another object of the present invention resides in the provision of an improved connection between adjacent cartridge belt links which includes novel means for limiting the relative helical movement therebetween to which the links are subjected during feeding of an ammunition belt along a path involving changes in direction.

10 Another object of the present invention is to provide an improved cartridge belt link adapted to be joined to the link adjacent thereto by a separate connector and of such construction that the body portion of one link cooperates with the body portion of the adjacent link to prevent the transfer of twisting forces to the connector.

A specific object of this invention is to provide a strong, non-deformable, disintegrating connection between adjacent lightweight cartridge belt links wherein the distance therebetween can be reduced to a minimum and still permit a limited amount of free helical twisting movement.

In carrying out the invention in one form, a one-piece cartridge belt link is provided with a spaced-apart pair of open cartridge-gripping loops having a substantially elliptical cartridge encircling portion therebetween of substantially channel-shaped cross section. One end of this elliptical portion is of greater width than the opposite end thereof. A ring-like connector fits over the larger end of the elliptical portion on one link and over the smaller end of the elliptical portion on the adjacent link to hold the links together during the feeding movements thereof. The diameter of the connector is selected to bring the adjacent links together to such extent that the walls of the channel-shaped smaller end of the elliptical portion on one link nest between the walls of the larger channel-shaped end of the elliptical portion on the adjacent link. As a result, twisting between adjacent links is limited to the extent permitted by the clearance between the walls of the smaller and larger channel-shaped ends of the elliptical portions of the respective links. This clearance is selected to limit the twisting between adjacent links so as to prevent the transmission of the resultant forces to the connector.

The specific nature of the invention as well as other objects and advantages thereof will clearly appear from a description of the preferred embodiment as shown in the accompanying drawing in which:

Fig. 1 is a side view of one of the links of the present invention;

50 Fig. 2 is an end view of the link of Fig. 1 looking at the front and smaller diameter cartridge-gripping ring segments;

Fig. 3 is a top view of the link together with a portion of an adjacent link to show the connection therebetween during normal feeding movement;

Fig. 4 is a transverse cross-sectional view taken along line 4—4 of the link connection of Fig. 3 but with the adjacent links twisted relative to one another;

Fig. 5 is an enlarged perspective view of the coupling portion of adjacent links to show the nesting relationship therebetween.

Fig. 6 is an enlarged view of the link of the present invention showing the manner in which the cartridge is stripped therefrom;

65 Fig. 7 is a view similar to Fig. 3, but showing an alternate construction for the connection between adjacent links;

Fig. 8 is an enlarged cross-section taken along the line 8—8 in Fig. 7; and

70 Fig. 9 is an enlarged perspective view of the alternate construction of the coupling portion between adjacent links.

Referring more particularly to the drawing, the invention is embodied in a unitary cartridge belt link having a longitudinally extending substantially arcuate body portion 12 and a pair of open cartridge loops 13 and 14 projecting laterally from the front and rear ends, respectively, of body portion 12. The opposite sides of loop 13 comprise substantially planar portions 15 projecting outwardly from body portion 12 at an obtuse angle thereto, as best shown in Fig. 2, to continue as opposite segments 16 of a cartridge-gripping ring. The free or terminal edges of segments 16 may be turned outwardly as shown at 17 in order to facilitate the insertion of a cartridge 19 therebetween. Segments 16 are arranged to blend integrally with the outer ends of planar portions 15 and to continue inwardly therebetween as shown at 18 in Fig. 2 for resiliently and releasably gripping cartridge 19. If desired, continuations 18 of segments 16 may meet and form an integral cartridge-gripping portion. However, it has been found that when separate segments 16 are employed as shown in Fig. 2, considerably greater resiliency is obtained.

Since the present invention contemplates the use of a link for holding a cartridge with a forwardly tapered case portion, the configuration of loop 14 is the same as loop 13 but is provided with cartridge-gripping segments 20 of larger diameter than segments 16. However, when non-tapered ammunition is employed, the cartridge-gripping rings of both loops 13 and 14 are arranged to be of equal diameter. Planar portions 15 are cut away as shown at 21 in Fig. 1 to expose the upper ends of ring segments 16 and 20 and thereby provide an opening for the entry of opposite inwardly turned flanges 30 on a link support rail 31 fixedly secured in the cartridge feeding apparatus (not shown). Rail 31 is provided with a depending stripper cam 32 at either end thereof outside the feeding path of the link as shown in Fig. 6. Thus, as the link moves along rail 31, cams 32 force cartridge 19 out from between ring segments 16 and 20 in a lateral direction relative to the longitudinal axis of body portion 12 for subsequent alignment with the bore axis of the firearm barrel.

The exterior periphery of body portion 12 is provided with an arcuate recess or may be channeled as best shown at 22 in Figs. 1 and 3 and such channel is continued along an arm 24 curving outwardly from body portion 12 beyond the peripheries of loops 13 and 14. A similarly channeled arm 23 of the same configuration as arm 24 but of lesser width relative thereto curves outwardly from the opposite side of body portion 12. Arms 23 and 24 combine to form an open ellipse whose major diameter is slightly above and substantially parallel to the transverse axes of ring segments 16 or 20.

Channel 22 of body portion 12 is necked down as shown at 25 to provide the difference in width between the channel-like configurations of arms 23 and 24. Thus, when the links of the present invention are to be coupled to one another to form a continuous belt, the smaller arm 23 of one link will nest within the larger arm 24 of the adjacent link, as best illustrated in Fig. 5, and are held in such relationship by a ring-like connector 26. It will be noted that the channel walls of arm 24 may be flared outwardly at the extreme ends thereof as shown at 27 in order to permanently retain connector 26 thereon.

Accordingly, when one link is twisted relative to the one adjacent thereto, the channel walls of arm 23 are brought into contact with the channel walls of arm 24 as best shown in Fig. 4 and not only stop further twisting movement between the links but also absorb any additional twisting forces imparted thereto after contact between arms 23 and 24. Testing of prior art links provided with similar ring-like connectors had revealed that the frequent breakages thereof were due primarily to the severe loads produced by adding these twisting forces to the normal tensile forces imparted thereto by the transverse belt pull encountered during feeding of cartridges into a gun. However, the nesting relationship of the links of the present invention substantially reduces the total forces

imparted to the connectors therebetween and thereby not only prevents breakage thereof but also permits a desirable decrease in the thickness of the metal from which the links are fabricated. However, if the strength of the link should prove marginal, embossed strengthening ribs 28 and 29 may be formed on body portion 12 and planar portions 15 of cartridge loops 13 and 14, respectively.

In the event a greater degree of relative twisting movement is required between adjacent links to compensate for the limited feeding space and consequent changes in directions of the guide chutes through which the ammunition belt is pulled, the difference in the widths of the channel portions of either of arms 23 and 24 may be varied to increase the clearance therebetween. Furthermore, the clearance between ring connector 26 and arms 23 and 24 in the nesting positions thereof can be controlled to provide a larger link pitch and easier disintegrating characteristics merely by enlarging the diameter of connector 26 accordingly.

In certain firearm designs a closer spacing of the adjacent cartridges may be required than that which can be obtained with the construction in which both arms 23 and 24 are of channel-like configuration as shown in Figs. 1-6. Accordingly, the present invention also contemplates a link wherein the arm having the narrower width, here indicated by numeral 33, is of simple rectangular cross-section as best shown in Figs. 8 and 9. The opposite and wider arm 34, however, is of the same channeled cross-section as that shown and described for arm 24 in Figs. 4 and 5. Arm 33 is, of course, arranged to fit between the channeled walls of arm 34 and to be held in such relationship by a rectangular connector 35. While the elimination of the channel-like configuration for one of the cooperating arms provides a somewhat weaker link coupling, the overall thickness thereof is no greater than the height of channeled arm 34 alone and consequently permits a much closer spacing between the adjacent links than is possible with the construction shown in Figs. 1-6. Since the width of this alternate connection is greater than the height thereof, a ring-like connector such as member 26 of Figs. 3 and 5 would permit excessive movement between arms 33 and 34. Accordingly, the shape of connector 35 is made rectangular in order to closely encircle the channel-like configuration of arm 34. The necessity for ease of manufacture may also require that connector 35 have a substantially rectangular cross-section as illustrated in Fig. 8. The end of arm 33 is, of course, curved sufficiently as shown at 36 to prevent separation between adjacent links during the feeding movements thereof into the firearm.

Thus, there is here provided an improved link of the type which can be coupled to an adjacent link by a separate connector without being subject to the frequent breakages heretofore encountered in the feeding of ammunition along tortuous paths in restricted areas. In addition, the nesting feature of this link permits a desirable reduction in the pitch thereof and consequently contributes toward increasing the rate of fire of the weapon.

Although a particular embodiment of the invention has been described in detail herein, it is evident that many variations may be devised within the spirit and scope thereof and the following claims are intended to include such variations.

I claim:

1. A cartridge belt comprising a plurality of successive cartridge-holding links, each of said links having a cartridge-gripping portion at either end thereof and an open cartridge-encircling loop of substantially elliptical contour centrally disposed between said cartridge-gripping portions, one end of said loop being of greater width than the other end thereof, said wider loop end having a channel-shaped cross-section, and connecting means for coupling adjacent links with the narrower end of said loop on one link disposed within the wider channel-shaped end of said loop on the adjacent link whereby the channel walls of

the latter intercept the forces normally imparted to said connecting means during helical twisting of the cartridge belt.

2. A cartridge belt comprising a plurality of successive cartridge-holding links and a ring member for coupling each of said links to the one adjacent thereto, each of said links having a cartridge-gripping portion at either end thereof and an open cartridge-encircling loop of substantially elliptical contour centrally disposed between said cartridge-gripping portions, said loop having a channelled cross-section of greater width at one end thereof than at the other, each of said ring members being positioned to encircle the adjacent ends of said loops on adjacent links and having a smaller diameter than the juxtapositioned height of said adjacent loop ends to provide a nesting relationship therebetween for intercepting the forces normally imparted to said connecting means during helical twisting of the cartridge belt.

3. A cartridge belt link comprising a longitudinal body portion, a cartridge-gripping portion at either end of said body portion, a first arcuate arm of channel-shaped cross-section extending outwardly and downwardly from the side of said body portion centrally between said cartridge-gripping portions, a second arcuate arm of wider channel-shaped cross-section extending from the opposite side of said body portion to cooperate with said first arm and form a substantially elliptical open loop, said loops on adjacent links being connected so that said first arm fits within the channel-shaped end of said second arm whereby relative movement between the adjacent links about the longitudinal axes thereof is limited by the engagement of said first and second arms of said loops.

4. A cartridge belt comprising a plurality of successive cartridge-holding links and a ring member for coupling each of said links to the one adjacent thereto, each of said links comprising a longitudinally extending body portion having oppositely divergent side portions adjacent either end thereof, a resilient ring segment integrally joined to each of said divergent side portions to form a pair of coaxial cartridge-gripping members, an open cartridge-encircling loop of substantially elliptical contour centrally disposed between said cartridge-gripping members, said loop having a channel-shaped cross-section of greater width at one end thereof than at the other, said ring member being positioned to encircle the adjacent ends of said loops on adjacent links and having a smaller diameter than the juxtapositioned height of said adjacent loop ends whereby said narrower channel-shaped end is disposed within said wider channel-shaped end to intercept the forces normally imparted to said ring member during helical twisting of the cartridge belt, and means on said wider loop end for preventing removal of said ring member therefrom.

5. A disintegrating cartridge belt comprising a plurality of successive cartridge-holding links and a ring member for coupling each of said links to the one adjacent thereto,

each of said links comprising a longitudinally extending body portion having oppositely divergent side portions adjacent either end thereof, an open resilient cartridge-gripping member disposed between the terminal ends of said divergent side portions, one of said cartridge-gripping members having a larger diameter than the other to accommodate a tapered cartridge, an open cartridge-encircling loop joined to said body centrally between said cartridge-gripping members, said loop having a substantially elliptical contour with a major diameter larger than either of said cartridge-gripping members, said divergent side portions having cutaway sections between said loop and said cartridge-gripping members to facilitate the lateral stripping of the cartridges therefrom, said loop having a channel-shaped cross-section of greater width at one end thereof than at the other, said ring member being positioned to releasably encircle the adjacent ends of said loops on adjacent links and having a smaller diameter than the juxtapositioned height of said adjacent loop ends whereby said narrower channel-shaped end is disposed within said wider channel-shaped end to intercept the forces normally imparted to said ring member during helical twisting of the cartridge belt, said loop having inwardly turned ends normally projecting outwardly beyond said ring member to prevent removal therefrom during the feeding movements of the cartridge belt.

6. The combination defined in claim 4 including outwardly flared corners on said wider loop end for permanently retaining said ring member thereon without preventing the release of said narrower loop end therefrom in the absence of feeding tension between adjacent links.

7. A cartridge belt comprising a plurality of successive cartridge-holding links, each of said links having an open cartridge-gripping portion at either end thereof from which the cartridges are adapted to be laterally stripped and an open cartridge-encircling loop of substantially elliptical contour centrally disposed between said cartridge-gripping portions, said loop being formed by a first arcuate arm of channel-like cross-section projecting from one side of the link and a second arcuate arm of rectangular cross-section projecting from the opposite side of the link, and a substantially rectangular connector for coupling adjacent links with said second arm disposed within the channel of said first arm whereby the walls thereof intercept the forces normally imparted to said connector during helical twisting of the cartridge belt.

8. The combination defined in claim 6 including outwardly flared corners on the end of said first arm for permanently retaining said connector thereon without preventing the withdrawal of said second arm from the interior of said connector.
